UNITED STATES PATENT OFFICE.

FRANK J. M. CURRAN, OF GRAND RAPIDS, MICHIGAN.

REFRIGERATOR CONSTRUCTION.

Application filed October 3, 1921. Serial No. 504,989.

To all whom it may concern:

Be it known that I, FRANK J. M. CURRAN, a citizen of the United States of America, residing at Grand Rapids, in the county of Kent and State of Michigan, have invented certain new and useful Improvements in Refrigerator Constructions; and I do hereby declare the following to be a full, clear, and exact description of the invention, such as

will enable others skilled in the art to which it appertains to make and use the same.

This invention relates to refrigerators, and is particularly concerned with interior construction for refrigerators, relating to the lining structure, the ice pan support and the dividing partition between the ice chamber and the provision chamber of the refrigerator. A primary object and purpose of the invention is to construct a very cheaply manufactured, simple yet durable and efficient interior refrigerator construction wherein the dividing partition is readily placed in position or as readily removed therefrom and in which the ice pan is supported in a novel and simple manner for ready removal or assembly. Many other objects and purposes subsidiary to the primary objects outlined will appear as understanding of the invention is had from the following description, taken in connection with the accompanying drawings.

Fig. 1 is a perspective view of the lining and ice chamber interior structure for a refrigerator.

Fig. 2 is a longitudinal vertical section substantially on the plane of line 2—2, of Fig. 4.

Fig. 3 is a horizontal section on the plane of line 3—3, of Fig. 2.

Fig. 4 is a transverse vertical section on the plane of line 4—4, of Fig. 2.

Fig. 5 is a plan of the blank from which the back, top and bottom of the lining is made.

Figs. 6 and 7 are elevations of the blanks for the two ends of the lining.

Fig. 8 is a fragmentary perspective and sectional view showing the manner of securing the ice chamber partition in place.

Fig. 9 is a fragmentary vertical section through one side of the ice drip pan.

Like reference characters refer to like parts in the different figures of the drawings.

In the construction of the lining, a blank of sheet metal is used including a back section 1 and top and bottom sections 2 and

3, respectively, as shown in Fig. 5, the top and bottom being bent forward at right angles to the back and each at its forward edge being provided with a vertical flange, 60 the top with flange 2^a and the bottom with flange 3^a for attachment to the front frame of the refrigerator, as will later appear. The back is provided with a vertical inwardly pressed rib 4 having a flat side 5 65 disposed at right angles to the plane of the back. It is also provided with a horizontal inwardly pressed rib 6 having an upper flat horizontal side or ledge 7, rib 6 being located at the lower end and to one side of the vertical rib 4.

One end of the lining is made by a plate 8 of sheet metal provided with a plurality of inwardly pressed horizontal shelf supporting ribs 9 and formed so as to have narrow inturned lips 10 at both vertical edges and similar parts 11 at its upper and lower edges which meet the ends of the top, bottom and back of the lining for welding thereto, thereby making a lining having rounded interior corners easy to keep in clean and sanitary condition. The opposite end of the lining is completed by a plate 12 of sheet metal provided with narrow inturned lips 13 at the vertical side edges and like lips 14 70 at the upper and lower edges to weld to the back, top and bottom of the lining at the other end. At the front, the parts 10 and 13 are bent into the form shown in Figs. 1 and 3 for connection to the front 75 frame of the refrigerator casing.

This front frame consists of lower and upper horizontal bars or rails 15 and 16, side posts 17, an intermediate vertical post 18 between the side posts 17 and an intermediate horizontal bar or rail 19 located between the post 18 and one of the side posts 17, the openings left in the frame defining the entrances into the ice chamber and provision chambers of the refrigerator. The 80 flanges 2^a and 3^a connect to the rails 16 and 15, respectively, and the outturned flanges on the parts 10 and 13 at the front of the lining connect to the side posts 17 as shown. The horizontal intermediate rail 19 has a horizontal ledge 20 on a triangular shaped rib 20^a, this ledge being in the same horizontal plane as the horizontal ledge 7 of rib 6 described.

An ice drip pan is adapted to rest on and 110 be located between the ledges 7 and 20. The pan is constructed of a wood core 21 cov-

ered with upper and lower sheet metal plates 23 and 22, the latter having upturned side flanges which cover the edges of the core and are then turned over similar but shorter upturned side flanges on the upper plate 23, thereby making a border flange entirely around the pan as indicated at 24. An opening 25 is made centrally in the pan and it is similarly surrounded by a like flange 24.

10 Water coming from the ice goes into the pan and any moisture collecting on the walls of the ice chamber is carried into the pan, following the guide strips 26 secured to the back and side 12 of the lining. The upper 15 edge of bar 19 is also provided with a guide 27 which, at its rear edge extends over the side flange 24 of the pan to carry any water collecting thereon to the pan. The usual drain pipe for refrigerators carries the water 20 to below the refrigerator, not being shown as not any particularly novel feature of the present invention.

A vertical partition completes the interior construction of the refrigerator, comprising a core 28 of wood covered with metal sides 29 and 30, the former of which is smooth and located on the ice chamber side while the latter is formed with a plurality of spaced apart horizontal ribs 31 adapted 30 to lie in the same horizontal planes with ribs 9 on the end 8 of the lining. This partition is placed at the inner end of the pan and rests thereon, at its rear edge coming against the side 5 of the vertical rib 4. 35 It is held in position against said rib by a gravity latch comprised of a short post 32 fixed to the back 1 of the lining and a latching member 33 pivotally connected thereto which is adapted to drop in front 40 of the side 29 of the partition and hold it in place, being readily raised for release of the partition whenever desired. The partition does not reach to the top 2 of the lining, there being a space 34 left making 45 a flue which with the flue opening 25 in the pan provides for the proper circulation within the refrigerator.

The pan may be covered with the usual corrugated metal ice holding plate or the 50 ice may be carried in a wire basket suspended from rods 35 connected to the top of the lining, in which case a thin metal cover will be used to keep the water from falling through the flue opening at 25.

55 This construction is very simple from a manufacturing standpoint and can be manufactured at low cost. The partition and drip pan are readily removable for cleaning and it is evident that the assembly is 60 particularly easy and simple. The front edge of the partition is received in a vertical groove 18* in the post 18, thereby serving, in connection with the latch at 33 to securely hold the partition in place. Simplicity in construction with corresponding

economy of manufacture are the primary advantages of the invention over other like constructions having the same functions. The appended claims define the invention and I consider myself entitled to all forms of construction coming within their scope.

70 I claim:

1. In a refrigerator, a lining having a back, top, bottom and ends and an open front side, a frame having door openings secured at the open front of the lining, said frame including a vertical intermediate post having a vertical groove at its rear side, a drip pan positioned horizontally between the frame and back of the lining at one side 80 of the lining, a vertically positioned partition resting at its lower end on one end of the drip pan and having its front face received in the groove of said post, means formed in the back of the lining against which a side of the partition at its rear face bears, and releasable means mounted on the back of the lining for holding the partition against said first means on the lining, substantially as described.

2. In a refrigerator, a lining having a back, top, bottom and ends and an open front side, a frame having door openings thereto secured at the open front of the lining, said frame including a horizontal bar or rail provided at its rear side with a horizontal ledge, said back of the lining having a horizontal rib pressed therefrom in substantially the same plane, a pan supported on said ledges, a vertical partition located at one end of the pan between the back and frame, said frame including a vertical post having a vertical groove on its rear side in which the front face of the partition rests, and means mounted on the back of the lining for releasably holding the partition in fixed relation to said back, substantially as described.

3. In a refrigerator, a lining having a back, top, bottom and ends and an open front side, a frame having door openings therethrough secured at the open front of the lining, said frame including a vertical post located intermediate the sides of the frame and a horizontal rail located between the upper and lower sides of the frame and between the said post and a side of the frame, said post being vertically grooved on its rear side and said rail having a horizontal rearwardly projecting ledge on its rear side, a horizontal rib pressed inwardly from the back of the lining in the same plane with said ledge, a vertical rib pressed inwardly from the back of the lining back of post, a pan supported on and between said ledge and horizontal rib, a vertical partition resting at one end of the pan, having its forward face received in the groove in the post and bearing at its rear portion against the vertical rib, and manually oper-

able latching means attached to the back of the lining and adapted to releasably engage with the partition to hold the same against said vertical rib, said partition terminating short of the top of the lining at its upper end.

4. In a refrigerator, a lining having a back, top, bottom and ends and an open front side, a frame having door openings therein and including an intermediate vertical post formed with a vertical groove in its rear face, a drip pan positioned horizontally between the frame and back of the lining and located at one side thereof, a vertically positioned partition resting at its

lower end on one end of the drip pan and having its front face received in the groove in the post, a vertical rib pressed inwardly from the back of the lining back of the post against which a side of the partition bears at its rear face, and a pivotally mounted gravity latching means mounted on the back of the lining to releasably engage with the partition at its opposite side and adjacent its rear face to detachably hold the partition in place, substantially as described.

In testimony whereof I affix my signature.

FRANK J. M. CURRAN.
